UNITED STATES PATENT OFFICE

2,475,223

AUTOMATIC WINDOW LOCK

Clarence J. Dawson, Detroit, Mich.

Application May 30, 1945, Serial No. 596,657

1 Claim. (Cl. 292—228)

1

This invention relates to an automatic window lock.

An object of the invention is the construction of a novel and efficient device for preferably retaining or holding sliding sashes in a closed position.

Another object of the invention is the construction of a novel and efficient lock in which means are provided for taking up the shock when the sashes to which the device is applied are tampered with, or are fraudulently attempting to be operated, such as when a burglar would be trying to raise or lower the sashes to enter the building, of which the sashes are a part.

A still further object of the invention is the construction of a novel and efficient window lock employing an anvil bar in connection with a peculiarly constructed latch bar, all being assembled in an efficient and novel manner.

With the foregoing and other objects in view, my invention comprises certain novel constructions, combinations and arrangements of parts as will be hereinafter fully described, illustrated in the accompanying drawings, and more particularly pointed out in the appended claim.

In the drawings:

Figure 1 is a view in elevation of a device constructed in accordance with this invention, shown in an applied position upon the window sashes.

Figure 2 is a sectional view taken on line 2—2, Fig. 1, and looking in the direction of the arrows.

Figure 3 is an enlarged vertical sectional view of the device.

Figure 4 is a sectional view taken on line 4—4, Fig. 3, and looking in the direction of the arrows.

Figure 5 is a perspective view of the casing.

Figure 6 is a perspective view of the elongated anvil bar.

Figure 7 is a perspective view of the U-shaped saddle bracket.

Referring to the drawings, in which the preferred embodiment of this invention is illustrated, 1 designates the lower sash and 2, the upper sash. The casing 3 is placed on the top of lower sash 1. This casing 3 comprises a hollow body 4 which has a cut-out portion 5, and is provided with two horizontal flanges 6. Screws 7 are employed for holding the casing in a secured position upon sash 1. The cut-out portion 5 has a pair of notches 7a for the purpose hereinafter described.

An elongated anvil bar 8 is employed, which has a saddle notch 9 in its top portion, and a bracket socket 10 formed in its lower face. A transversely positioned depending lip 11 is on the inner end of anvil bar 8, which lip extending

2

down against a portion of the inner face of the lower sash 1, as clearly seen in Figure 3. This lip 11 serves to remove considerable of the strain off screws 7, whereby the casing 3 is securely retained in position.

A U-shaped saddle bracket 12 is employed, the bracket being placed in bracket socket 10, and apertures 13 of said bracket register with the saddle socket 9.

10 A latch bar 14 has its inner or lower end resting down between the sides of said saddle bracket 12, with a bolt 15 extending through apertures 13 and the large aperture 16 in said latch bar 14; said bar is adapted to swing or move in a vertical plane parallel to the longitudinal axis of said anvil bar. Any blow upon the upper end of the latch bar 14 will not cause any strain on bolt 15, because its aperture 16 is sufficiently large to permit the lower or inner end of said latch bar 14 to strike or engage firmly the saddle socket 9 of the anvil bar 8; this novel construction greatly increases the life of the device, by reason of the strain being entirely removed from bolt 15.

15 20 25 30 35 40 45 50

25 The elongated latch bar 14 has a knob or grip 17 near its upper end, which the operator grasps when he desires to manipulate the device. The latch bar 14 is provided with a notch 18 on its upper or outer end, and with a lip 19. The latch bar 14 is slightly rounded at 20, Fig. 3, so that it will not cut into the upper sash 2; further, by this peculiar construction, the bar is easily manipulated by the operator for removing the bar from its locked position, or permitting it to assume a locked position. A keeper plate 21 is provided, which is adapted to receive the upper or outer end of the latch bar 14, as clearly illustrated in the drawings. The notched end 18 of said latch bar normally engages the upper portion of the keeper plate 21, when the device is in its locked position.

An elongated flat spring 22 is provided, with its lower end in the casing, on top of the anvil bar 8, as clearly seen in Figure 3. The upper end of flat spring 22 normally presses against the latch bar 14, for exerting inward pressure upon said bar, whereby it assumes automatically its locking position when the two sashes are in the position shown in the drawing. The operator can easily grasp grip 17 and swing the latch bar 14 outwardly (Fig. 3) when it is desired to release the device, whereby the sashes can be vertically adjustable to the desired position.

55 While I have described the preferred embodiment of my invention and illustrated the same

in the accompanying drawings, certain minor changes or alterations may appear to one skilled in the art to which this invention relates during the extensive manufacture of the same, and I, therefore, reserve the right to make such changes or alterations as shall fairly fall within the scope of the appended claim.

What I claim is:

In a device of the class described, the combination of a hollow elongated casing having an open bottom and a closed outer end and an open inner end and a partly closed top, an elongated anvil bar filling said casing and closing the inner open end of said casing, said anvil bar provided on one end with a sash-engaging lip depending below the bottom face of said anvil bar; a U-shaped saddle bracket within said casing and engaging the bottom and two sides of said anvil bar, said saddle bracket having its upper portion extending through the top of said casing, a latch

bar above said anvil bar and in continuous engagement therewith, and means fastening said latch bar to the extended upper end of said U-shaped saddle bracket.
